UNITED STATES PATENT OFFICE.

HENRY STENZ AND GEORGE WESTERMANN, OF FARIBAULT, MINNESOTA,
ASSIGNORS TO THE SHADOWLESS RADIATOR MANUFACTURING COMPANY,
OF SAME PLACE.

RADIATOR ATTACHMENT FOR ARC-LAMPS.

SPECIFICATION forming part of Letters Patent No. 599,519, dated February 22, 1898.

Application filed November 30, 1896. Serial No. 613,980. (No model.)

To all whom it may concern:

Be it known that we, HENRY STENZ and GEORGE WESTERMANN, citizens of the United States, residing at Faribault, in the county of 5 Rice and State of Minnesota, have invented a new and useful Radiator Attachment for Arc-Lamps, of which the following is a specification.

This invention relates to arc-lamps; and it 10 has for its object to provide a new and useful attachment for lamps of this character having means for securing a uniform radiation or diffusion of the light, so as to increase the brilliancy thereof, while at the same time 15 being especially designed for the purpose of obviating or diminishing the shadow cast by the side bars of the lamp-frame, which shadow is an objectionable feature of arc-lamps now in use.

With these and other objects in view, which 20 will readily appear as the nature of the invention is better understood, the same consists in the novel construction, combination, and arrangement of parts hereinafter more 25 fully described, illustrated, and claimed.

In the drawings, Figure 1 is a perspective view of an arc-lamp fitted with one form of the herein-described invention. Fig. 2 is a detail in perspective of one of the segmental 30 radiator attachments removed from the lamp-frame. Fig. 3 is a vertical sectional view of the construction illustrated in Fig. 2. Fig. 4 is a cross-sectional view on the line 4 4 of Fig. 3. Fig. 5 is a view similar to Fig. 1, showing 35 a circular or cylindrical form of the attachment employed as a substitute for the ordinary arc-light globe. Fig. 6 is a vertical sectional view of the form of attachment illustrated in Fig. 5. Fig. 7 is a cross-sectional 40 view of the circular or cylindrical form of the attachment. Fig. 8 is a top plan view thereof.

Referring to the accompanying drawings, it 45 will be seen by reference to Figs. 1 to 4, inclusive, that these figures of the drawings illustrate one form of the radiator attachment, which, while serving to secure a uniform radiation or diffusion of the light, is primarily designed to so diffuse the light as to obviate a shadow being cast by the side bars of the

lamp-frame, and in this form of the attachment the radiator is used in conjunction with the usual lamp-globe (not shown) and occupies a position interposed between the light and the side bars of the lamp-frame.

Referring particularly to Figs. 1 to 4, inclusive, the numeral 1 designates an arc-lamp of any approved form, having the usual carbons 2, and the frame thereof essentially comprising the oppositely-located parallel side bars or rods 4, and in Fig. 1 of the drawings the usual globe of the lamp is omitted, so as to expose to view the proper relative position of the oppositely-located radiator attachments for the opposite side bars 4 of the lamp-frame. Each of the oppositely-located 55 radiator attachments (designated by the numeral 5) essentially comprises a pair of spaced upper and lower frame-plates 6 and a plurality of solid glass rods 7, arranged closely together between the oppositely-located frame-plates and forming a solid transparent light-radiating body. The oppositely-located upper and lower frame-plates 6 are provided in 60 their inner faces with the segmental grooves 8, receiving the ends of the glass rods 7, so 65 as to hold the rods disposed in the same circular plane and thereby produce a light-radiating body concavo-convex in cross-section, with corrugated convexed and concaved surfaces, it being observed that the rods are arranged closely together and in parallel vertical planes, so as to leave no space between 70 their adjacent faces through which the light can shine.

The upper and lower frame-plates 6 of the 85 attachment are somewhat triangular in form and project laterally beyond the convexed side of the radiating-body and have formed in such laterally-projected portions the rod-openings 9, receiving the opposite bolt ends 90 10 of a tie-rod 11, connecting the two plates, and which when tightened at its bolt ends serves to tightly clamp the plates onto the ends of the glass rods, so as to hold such rods rigidly in place and form the light-radiating 95 body. The frame-plates 6 are provided at their outer corners or edges with the rest-notches 12, forming projections which engage

against the side bars 4 of the lamp-frame to hold the radiator attachment in a plane parallel with the side bar of the frame and between such side bar and the arc-light, and to 5 provide for detachably securing the attachment in this position attaching-wires 13 may be conveniently employed, which wires are strung through wire-openings 14 in the plates 6 and are adapted to be twisted around the 10 frame side bar 4 to which the attachment is fitted.

It will of course be understood that a separate one of the attachments described is arranged at each side of the arc-light and is secured to each of the side frame bars or rods 15 4 at the inner sides of the said side bars to provide for intercepting the light and radiating or diffusing the same in such a manner as to obviate the casting of a shadow by the 20 said side frame bars.

It will be observed that when the radiator attachments are positioned as described the inner corrugated concaved surfaces of the radiating-bodies are disposed next to the light 25 and have somewhat of a prismatic effect, causing the light to be widely radiated and evenly diffused without the casting of any shadows.

A modified form of the attachment is illustrated in Figs. 5 to 8 of the drawings, in which 30 form of the attachment the solid transparent light-radiating body is formed by a continuous circular series of the solid glass rods 7, arranged closely together in the same circular 35 plane and in parallel vertical planes to produce a complete circular or cylindrical radiating-body that is designed to entirely encircle the carbons of the lamp, and thereby dispense with the use of the ordinary lamp-globe. 40 In the modified form of the attachment having a complete circular or cylindrical light-radiating body the rods 7 are arranged between a pair of spaced upper and lower circular frame-plates 15 in the form of rings and 45 provided in their inner faces with the circular or annular grooves 16, receiving the ends of the rods 7 to hold the same properly in position, so as to produce a solid light-radiating body of the form described, and the said opposite circular frame-plates 15 are provided with laterally-projected vertically-aligned perforated ears 17, which are connected by the tie-rods 18, having bolt ends 19, engaging with the ears 17, whereby the opposite frame- 50 plates 15 may be drawn tightly together onto the ends of the continuous circular series of the rods 7. The circular frame-plates 15, with the circular or cylindrical light-radiating body clamped therebetween, form what may 55 be properly termed a "radiating-globe" for the lamp and are designed to be fitted within the frame of the lamp between the opposite side bars 4 thereof, so as to occupy the position of the usual lamp-globe, but having the 60 additional function of thoroughly diffusing the light and preventing the casting of shad- 65

ows from parts of the frame adjacent to the light.

The oppositely-located frame-plates 15 of the circular or cylindrical form of the attachment are provided at diametrically opposite edges with the offstanding stop-lugs 20, adapted to rest against one side of the opposite frame side bars 4 when the attachment is placed between such side bars, and arranged 70 on the uppermost frame-plate 15, so as to work directly above the stop-lugs 20 thereof, is a pair of diametrically opposite catch-dogs 21. The diametrically opposite catch-dogs 21 are provided at their inner ends with 75 the pivot-tongues 22, pivotally mounted between the ears 23, projected from the said upper frame-plate 15, and on their upper sides the said catch-dogs 21 are formed with finger projections 24, whereby the dogs may 80 be readily manipulated. The said catch-dogs 21 are provided with bifurcated or forked outer ends 25, adapted to frictionally embrace the inner sides of the frame side bars 4, so as to hold the attachment properly in place, it 85 being observed that the stop-lugs 20 for the upper frame-plate 15 are disposed at one side of the bifurcations or forks 25 of the said dogs 21. After the cylindrical form of the attachment is inserted in place between the frame-bars 4 the catch-dogs 21 are forced down 90 against the said bars 4, so as to rigidly fasten the radiator attachment in position. When trimming the carbons, the catches 21 are raised, so as to permit of the attachment being 95 slid in an upward direction, after which the said catches are again forced into binding engagement with the bars 4, so as to secure the attachment in its elevated position until the trimming is finished. For cleaning 100 the cylindrical form of the attachment the dogs 21 are thrown entirely out of the way, thereby permitting the attachment to be moved laterally from between the side bars 105 of the frame. 110

In the cylindrical form of the attachment just described the closely-contacting solid glass rods form a light-radiating body having corrugated concaved and convexed surfaces, with the corrugated concaved surface disposed next to the light to secure the proper 115 radiation or diffusion thereof. 120

While the light-radiating body has been described as being preferably formed of a plurality of solid glass rods, which are easily replaceable when broken, still it will be understood that such body may be formed of a single casting of glass having the same corrugated conformation as the rod-body and thereby necessarily attaining the same results. 125

Other changes in the form, proportion, and the minor details of construction may be resorted to without departing from the principle or sacrificing any of the advantages of 130 this invention.

Having thus described the invention, what

is claimed, and desired to be secured by Letters Patent, is—

1. A radiator attachment for arc-lamps comprising a pair of oppositely-located frame-
5 plates having grooves in their inner faces, and projections at their edges adapted to en-
gage the adjacent side bar of the lamp-frame, an adjustable tie-rod connection between the
two plates, a plurality of vertical glass rods
10 arranged side by side in the same circular
plane and having their inner ends fitting the
grooves of the frame-plates, and fastening
means for securing the attachment to the
lamp-frame, substantially as set forth.
- 15 2. A radiator attachment for arc-lamps, comprising a pair of oppositely-located adjust-
ably-connected circular frame-plates having
grooves in their inner faces, a continuous cir-
cular series of solid glass rods arranged closely
20 together with their ends fitting in the grooves
of said plates, and movable catches mounted
on one of said frame-plates and adapted to be

inoved in and out of engagement with the
side bars of the lamp-frame, substantially as
set forth.

- 25 3. A radiator attachment for arc-lamps comprising a pair of oppositely-located circular
frame-plates provided at diametrically oppo-
site edges with stop-lugs, a continuous circu-
lar series of solid glass rods arranged closely
30 together and clamped between said frame-
plates, and bifurcated or forked catch-dogs
pivotally mounted on the upper of said frame-
plates and arranged to work directly above
the stop-lugs of said plates, substantially as
35 set forth.

In testimony that we claim the foregoing as
our own we have hereto affixed our signatures
in the presence of two witnesses.

HENRY STENZ.

GEORGE WESTERMANN.
